No. 738,603.

Patented September 8, 1903.

UNITED STATES PATENT OFFICE.

HAYDN BROWN, OF LONDON, ENGLAND.

SYRINGE-NOZZLE.

SPECIFICATION forming part of Letters Patent No. 738,603, dated September 8, 1903.

Application filed January 13, 1902. Serial No. 89,440. (No model.)

To all whom it may concern:

Be it known that I, HAYDN BROWN, a subject of the King of Great Britain, residing at 44 Hamilton Gardens, St. John's Wood, London, England, have invented a new and useful Improvement in Syringe-Nozzles, of which the following is a specification.

My invention relates to an improvement in syringe-nozzles, and is intended to be attached to the tubing of enema-syringes, siphon vessels, or douche-cans to be passed into the vagina for surgical or hygienic purposes, fluid being driven through it into the vagina. I attain these objects by the mechanism illustrated in the accompanying drawings, in which I represent a section of the syringe-nozzle with a slit or opening in the bulb. Figure 1 is a longitudinal section of the vaginal-tube, and Fig. 2 is a section on line A B of Fig. 1.

Letters refer to parts throughout the views.

In the figures the bore b is made to terminate in a circle at k at or not far from the center of the bulb a, and this is met by a slit or opening n, beginning at or near the extreme end m of the bulb, which said slit or opening is continued until it cuts into the termination of the circular end of the bore. Thus a slit effects an expansion of bore equiv-

alent to the circular enlargement of the bore, 30 but having the advantage of spreading a fluid which is projected through the slit and further preventing particles from returning back into the appliance in a return flow through the slit. The narrow slit will prevent certain 35 pieces of debris from being washed back and yet permit free flow forward.

The nozzle is an enlarged bulb a and a neck o at the end of the shaft b with the bore.

What I claim as my invention, and desire 40 to secure by Letters Patent, is—

In a syringe-nozzle, the combination of an enlarged spherical bulb, a shaft connected therewith provided with a bore terminating in a semispherical end at or near the center 45 of the bulb, and the said bulb being provided with a slit beginning at the extreme end thereof and continuing toward the opposite end until it meets the bore of the shaft at the semispherical end thereof, substantially as 50 described.

In testimony whereof I have signed my name to this specification in the presence of two subscribing witnesses.

HAYDN BROWN.
